UNITED STATES PATENT OFFICE.

CHARLES HICKS, OF LANDPORT, ENGLAND.

MEANS FOR TUNING PIANOFORTES.

SPECIFICATION forming part of Letters Patent No. 601,322, dated March 29, 1898.

Application filed December 4, 1897. Serial No. 660,771. (No model.)

To all whom it may concern:

Be it known that I, CHARLES HICKS, a subject of the Queen of Great Britain and Ireland, and a resident of 199 Fratton road, Landport, in the county of Hampshire, England, have invented certain new and useful Improved Means for Tuning Pianofortes and other Stringed Instruments, of which the following is a specification.

10 The object of my invention is to provide simple and efficient means whereby the operation of tuning pianos and other stringed instruments—that is to say, adjusting of the tensile strain upon any wire or string—may be effected not only with ease and rapidity, but also with greater delicacy and accuracy than heretofore. For this purpose, according to my invention, I employ specially-constructed adjustable rotary pegs or plugs, which may 15 be used either alone or in connection with the usual pegs or any conveniently-fixed point, and these, together with their operation and use, I will now fully describe in reference to the accompanying drawings.

20 Figure 1 is a sectional elevation showing the three component and coacting parts of one of my improved tuning-pegs loosely assembled. Fig. 2 is a similar view showing them put together and screwed down. Fig. 3 is a similar view showing a complete peg fixed into the tuning-board of a pianoforte with a wire attached. Fig. 4 is a front elevation of my improved peg, showing its use in connection with an ordinary or fixed peg; 25 and Fig. 5 is a part view showing the general arrangement in a pianoforte of the latter method of using my improved pegs.

30 My improved tuning-peg consists of three parts, viz., first, a tubular nut N for fixing in the tuning-board; second, a coned operating-plug P, screwed thereinto, and, third, a loose annular collar C.

35 The shank of the plug P is screw-threaded about its lower part p and has at its upper part a coned shoulder p' , surmounted by a collar p^2 and a squared head p^3 for receiving the tuning-key. The tubular nut N has a central opening o and has a female screw n at its base of less diameter than that of the opening o . The head is open to receive the plug P and may either be coned internally at n' to correspond with plug-cone p' , or it may

have a cylindrical recess equal in diameter to the largest diameter of the cone p' , so that in either case the cone p' can enter the recess n' 55 for its full length. The annulus of the collar C may be parallel-sided, but it is preferably coned internally, and it has a flange c to serve as a bearing for the cone-collar p^2 , and a peripheral groove c' is formed for the reception of or fixing of the wire or string W.

When the three parts are not tightly screwed up, as will be seen, there is a slight play between the plug P and the nut N, owing to the difference of diameters of the plug-shank p and the space o . This is provided in order to allow greater range of motion of the parts in tuning. (See, for example, Fig. 3, where the tension of the wire W imparts a slightly-inclined position to the plug P as long 70 as it is not screwed in tightly.)

Fig. 3 shows the peg used alone and screwed into the tuning-board B of a piano, the wire being attached to the ring-collar. Fig. 4 shows the wire passing over the ring C as a 75 pulley and fixed at its end to an ordinary or fixed peg T. For convenience in fixing and removing the nut N it is threaded for a suitable distance d externally and provided with cross-cuts d' in its head to receive a simple 80 screw-driver. Preferably these tuning-pegs, together with the fixed pegs T, if used, are fixed to the upper tuning-board B of an instrument, and the other end of the wire W is attached to one of the usual steel pegs T' on 85 the other or lower tuning-board B', the arrangement being such as is illustrated in Fig. 5. As will be seen, the ring C will slide upon the cone p as the plug P is screwed into or 90 out of the nut N, and according to its position thereupon, whether the wire be fixed to the ring C or passed over same and fixed to peg T, so is the strain upon the wire W increased or decreased by simple turning of the plug P and in a delicate and positive manner. Assuming a position of the parts such as Fig. 3 and the tone flat, to tighten the string the cone P is to be screwed farther into the nut N, and the ring C, sliding up the ingoing cone p' , tightens the string W, 100 and by the reverse operation the tension on the string will be released and the tone flattened.

Having now described my invention, what

I claim as new, and desire to secure by Letters Patent, is—

An adjustable rotary tuning-peg for pianofortes and other stringed instruments adapted for use alone or in connection with ordinary or fixed pegs, consisting of the combination of three component coacting parts, viz., a tubular nut N for fixing in the tuning-board, a coned operating-plug P screwed thereinto, 5 and an annular collar C to which the wire is attached or over which it passes to an ordinary peg, the tensile strain on the said wire 10

being adjusted as required, by regulating the position of the ring C on the cone p' by operating the plug P, the whole combination 15 being constructed and adapted to operate substantially as described and illustrated.

In witness whereof I have hereunto set my hand in presence of two witnesses.

CHAS. HICKS.
